ELECTRONIC CALCULATING MACHINE

Isao Kitai, Osaka, Japan, assignor to Sharp Kabushiki
Kaisha, Osaka, Japan

Filed Nov. 28, 1975, Ser. No. 636,123

Claims priority, application Japan June 4, 1975

Term of patent 14 years

Int. Cl. D18—01

U.S. Cl. D26—5 C

FIG.—1

FIG.—2

FIG.—3

FIG.—4

FIG.—5

FIG.—6

FIG.—7

FIG. 1 is a front perspective view of an electronic calculating machine showing my new design;

FIG. 2 is a top plan view;

FIG. 3 is a front elevational view;

FIG. 4 is a rear elevational view;

FIG. 5 is a right side elevational view;

FIG. 6 is a left side elevational view; and

FIG. 7 is a bottom plan view.

I claim:

The ornamental design for an electronic calculating machine, as shown and described.
